DESIGN FOR SUNGLASSES

Edward K. Madan, Maplewood, N. J.

Application April 29, 1938, Serial No. 76,853

Term of patent 3½ years

To all whom it may concern:

Be it known that I, Edward K. Madan, a citizen of the United States of America, residing at Maplewood, in the county of Essex and State of New Jersey, have invented a new, original, and ornamental Design for Sunglasses, of which the following is a specification, reference being had to the accompanying drawing, forming part thereof.

The figure of the drawing is a perspective view of the sunglasses showing my design.

The characteristic features of my design reside in the combination of a spectacle frame of the configuration shown, having permanently attached thereto in the manner as disclosed, front and side shade members also of a configuration as shown.

I claim:

The ornamental design for sunglasses, as shown and described.

EDWARD K. MADAN.
